Specification for Design.

Patented Nov. 23, 1915.

Application filed July 3, 1915. Serial No. 38,039. Term of patent 14 years.

To all whom it may concern:

Be it known that I, BELA ZWACK, a subject of the Emperor of Austria-Hungary, residing at Budapest, Austria-Hungary, have invented a new, original, and ornamental Design for a Bottle, of which the following is a specification, reference being had to the accompanying drawings, forming part thereof.

The figures are perspective views of the bottle, showing my new design.

Figure 1 is a perspective view, looking from above, of a bottle illustrating my new design; Fig. 2 is a perspective view, looking from the right side thereof; and Fig. 3 is a perspective view, looking from the front.

I claim:—

The ornamental design for a bottle, substantially as shown.

B. ZWACK.
